SIGHT FOR GUNS

Nels A. Nelson and Frank G. Nicolaus, Chicago,
Ill., assignors to Raymond T. Moloney, Chi-
cago, Ill.

Application August 21, 1940, Serial No. 353,492

4 Claims. (Cl. 240—6.41)

The invention relates to guns and more particularly to an improved sight therefor.

In the particular case of light ray shooting guns, it is found that frequently they are used in interiors which are not too well lighted and as a result the sight of the gun is of no service in aiming of the gun at the target, because it cannot be seen.

It is thus desirable to provide a gun sight for such guns, which will be readily visible even when the gun is used with target apparatus placed in darkened interiors.

The main object of the invention is to provide an improved gun.

Another object is to provide such a gun having an improved gun sight.

Still another object is to provide a gun sight that will be visible for use even if the gun is used in dark places.

A further object is to provide a gun having an illuminated gun sight.

Further, it is an object to provide a light ray shooting gun with an illuminated gun sight.

Other important objects will become apparent as the disclosure is more fully made.

Briefly, in a preferred embodiment as herein disclosed, a light ray shooting gun having an aiming sight associated with the muzzle end of the gun, is provided at such end with means to illuminate the sight to make same at all times visible and without interfering with the "bullet" of light fired by the gun, all as shown in the accompanying sheet of drawings, wherein:

Figure 1 is a side elevational view of the improved light ray shooting gun with parts broken away in section; a typical wiring diagram for the electric lights being also illustrated;

Figure 2 is an enlarged, cross sectional view through the gun muzzle, taken along line 2—2 of Figure 1, looking in the indicated direction;

Figure 3 is a plan view, on the same scale, of the muzzle end of the gun; and,

Figure 4 is a side elevational view, partly in section, and on the same scale, of the muzzle end of the gun.

The gun comprises a stock 10 including a tubular portion 11, carrying a sleeve unit 12 supporting an electric lamp 13 and a light condenser lens 14. Positioned in the portion 11 is a gun barrel 15, including along its front lower end a hand hold or rest portion 16, the forward end of which is hollowed out below the barrel's muzzle to provide a cavity 17.

The muzzle carries a projector lens 18 and an outer sleeve 19, including an upstanding vane 20

forming the gun sight, which alines with a rear gun sight 21 to enable the marksman properly to aim the gun before shooting the same. The electric lamp 13, by means of a wire 22 is in circuit with a source of electrical energy 23; a return wire 24 going to one side of a normally open, spring blade contact switch 25 carried in the portion 11 of the gun beneath its barrel 15 in the manner shown in Figure 1. A wire 26 goes from the other side of the switch 25 back to the lamp 13 to make a complete circuit. A pivoted trigger 27 is carried in the portion 11 proximate the switch 25 and a hand grip portion 28, so that when the marksman operates the trigger 27 with his finger, the switch 25 is closed to cause the lamp 13 to light and send its flash or ray, because of the lenses 14 and 18, through the barrel 15 to the target objective, all as is well understood in this art.

In the muzzle cavity 17 is positioned a bracket and socket 29 for carrying an electric lamp 30 in circuit by wires 31 and 32 with the source of energy 23. A master switch 33 is in this circuit and in practice may be closed by an appropriate coin released mechanism so that as soon as the gun is picked up by the marksman for use the lamp 30 will be lighted and remain so during the entire time the gun is available for use to the marksman. The barrel 15 of the gun directly over the light 30 is formed with vertically alined, diametrically disposed, apertures 31' and 32'. Thus, the light emanating from the lamp 30 passes upwardly through the holes 31' and 32' and illuminates the rear edge 20' as well as opposite sides of the sight 20. This is so, because the sight 20 lies in a vertical plane passing through the center of the holes 31' and 32', and the said holes are wider than said sight. The ray of light from the lamp 13 passes freely through the barrel, cutting through the light from the lamp 30 at a right angle without interference.

It can now be appreciated that an improved gun and gun sight has been provided which achieve the objects for the invention heretofore recited.

The intention is to cover all changes and modifications not departing from the spirit and scope of the invention as defined in the appended claims.

What is claimed is:

1. In a gun having a barrel and a sight at its muzzle end, means associated with the barrel to illuminate said sight, said means comprising an electric lamp carried beneath the barrel on the side thereof opposite the sight, and said barrel

having vertically alined openings formed therein below the sight whereby light from the lamp passes upwardly diametrically through the barrel to illuminate the sides and an edge of the sight.

2. In a gun having a barrel, a sight thereon having sides and a sighting edge, and an electric lamp carried beneath the barrel proximate the sight, said barrel having openings formed vertically therethrough and positioned to illuminate opposite sides and the sighting edge of said sight, said edge overhanging the openings to receive direct illumination therefrom.

3. In a gun barrel having a vane sight thereon with a sighting edge, said barrel having diametrically disposed holes formed therein, a lamp

carried below the barrel to send light through the holes to the sight, said upper hole being bisected by said sight so that light hits both sides thereof.

4. In a gun barrel having a vane sight thereon with a sighting edge, said barrel having diametrically disposed holes formed therein, a lamp carried below the barrel to send light through the holes to the sight, said upper hole being bisected by said sight so that light hits both sides thereof, the sight edge furthermore overhanging the upper hole by undercutting the vane sight, whereby light from the upper hole directly hits said edge.
